TOWER TOP FOR LOGGING SPAR

Reid G. Priest and Dean K. McCurdy, Port Angeles, Wash., assignors, by direct and mesne assignments, to Hyster Company, Portland, Oreg., a corporation of Nevada

Filed Oct. 28, 1963, Ser. No. 319,219

2 Claims. (Cl. 212—70)

This invention relates to new and useful improvements in logging equipment and more particularly to new improvements in a tower top and fair-lead assembly situated at the top of a mobile and portable spar used in logging operations.

In logging operations as previously carried out in the lumbering areas of the United States, suitable spar trees would be selected and rigged for logging. In recent years logging has gone further into the hills and it has become increasingly more difficult to find suitable trees to be used as spars. Furthermore, operating costs have increased manyfold and this economic fact, along with the lack of spar trees, has given rise to the use of portable prefabricated spar towers that are transported horizontally and partially dismantled from location to location by truck, tractor or sled and are then erected and guyed at the selected location.

One of the problems which accompanies the use of new portable type spar towers is that of an effective and acceptable tower top and fair-lead assembly. One of the factors which has operated to make currently known tower tops unacceptable is that there is no provision for avoiding tangling and wearing of the main and haul back cables which are reeved through the tower top. Such lack of separation causes rapid wear and all too frequent replacement of the cables. Additionally, present devices require large bearing structures because of their design which places the load carrying and thrust support elements too far below the blocks. Furthermore, design deficiencies dictate that they be made heavier in order to compensate for design and also that the bearings be large in order to contain the necessary strength.

The tower top and fair lead assembly of this invention seeks to overcome the disadvantages of heretofore known devices by departing from conventional design standards. In effect, the tower top and fair lead assembly of this invention provides for reeving the main and haul back cables over free turning sheaves or fair leads which have their vertical axes of rotation non-concentric or non-coincident. Furthermore, the heavy bearing structures which are necessary in presently known devices are done away with since the moments created at the tower top by the forces exerted on the cables are reduced. In effect, the tower top sheave mounting structure is rigid to a point above the main block and to a point just below the horizontal shaft of the haul back sheave.

Accordingly, it is a feature of this invention to provide a tower top which because of the spaced axes of the main and haul back block pivots eliminates the rubbing and twisting and consequent wearing of the two cables since they are maintained or threaded through the assembly in distinctly separate channels.

Another feature of this invention is to supply a tower top assembly which reduces the moments or thrust created by the cables and the bearings thus enabling the

2

design to employ smaller bearings and to be lighter in structure.

Still another feature of this invention is to furnish a tower top assembly which may be attached to a tower of any height.

Still another feature of this invention is to provide a tower top assembly which permits the angle of cant of the tower top assembly to be varied according to the nature of the engine and winch equipment used for the yarding operation.

A further feature of this invention is to furnish a tower top assembly which is simple in design, rugged in construction and economical to produce.

These, together with other features and advantages which will become subsequently apparent, reside in the details of the construction and operation as more fully hereinafter described and claimed. Reference will be had to the accompanying drawings, forming a part hereof, wherein like numerals refer to like parts throughout, and in which:

FIGURE 1 is an environmental illustration, essentially diagrammatic, showing a portable type logging tower base and spar and showing where the tower top and fair lead assembly of this invention is included in the operation;

FIGURE 2 is a side elevational view of this structure showing in greater detail the general arrangement of the parts and elements contained therein; and

FIGURE 3 is a section view taken through the horizontal center of the device to more clearly illustrate the details of its construction.

Referring now to the drawings, and especially FIGURE 1, it will be seen that the environment in which this invention is used is comprised generally of a mobile power base unit 10. The tower base is shown in the drawings to be truck mounted merely for the purposes of illustration. Numerous other methods for transporting the tower base unit are known and will readily occur to persons skilled in the art. Truck 12 and its tower base extension carry yarder engine 14, haul back winch 16, main winch 18, and the tower hoisting frame apparatus 20. The tower itself generally shown by number 22 has guyline drums 24, tower base supporting means 26, and the tower top and fair lead assembly generally shown by the number 30.

As can be seen from FIGURES 2 and 3 the tower top has the haul back sheave 32 and the main cable sheave 34. The main sheave 34 has reeved thereover the main cable 36 while the haul back sheave 32 has reeved thereover the haul back cable 38. The sheaves are supported at the top of the tower 22 by a supporting housing generally designated by the number 40. Housing 40 is a single piece casting which is either welded or bolted at an angle as at 42 to the tower top. Housing 40 is such as to cover the whole of the tower top and to extend outwardly rearwardly thereof. The angle line 42 at which the housing is secured to the tower is determined primarily by the nature of the engine employed to drive the haul back and main cable winches. The yarder engine and winches could be close to the base of the tower in which case the angle from the horizontal along the line 42 would be slight. On the other hand, if the power unit is located somewhat away from the tower base then the angle would become slightly greater from the horizontal.

Housing 40 has a base section 44 extending from the

front of the tower as at 23 and extending out from the rear line 25 of said tower to point 46 forming the lower and rear most point of the housing 40. The rear of housing 40 is a generally upstanding long tapering, essentially frusto-conical, tubular haul back support section 48 which is open at the bottom thereof. For purposes of comparison it should be understood that the dimension from the line 42 at the base of housing 40 to the top of the tubular haul back support section 48 is approximately 44 inches. The upper portion 50 of the housing 40 extends outwardly generally parallel to the base portion 44 for approximately half the distance as said base section 44.

An opening 76 is provided below and coaxially aligned with bearing support portions 74. It will be appreciated that the upper section 50 of the tower top housing 40 is provided with another opening 72 to permit a detachable or removable generally round bearing cage 78 to be dropped therein. Bearing cage 78 has upper support flanges 80 which permit the cage to be set into opening 72 in a position for quick attachment to the main housing 40. Bearing cage 78 is removable because of the manner in which the main block 80 is attached to the main housing. Note that a generally tubular main block support portion 82 has tapering ends 84 and 86. Bearing cage 78 has the depending cylindrical bearing support portion 81 for receiving the upper main thrust bearing 88. In like manner the bearing support portion 74 at the base supports lower main thrust bearing 90. Thus, the upper end of the upper tapering end 84 of the main block 80 is received into the bearing support section of the bearing cage. In like manner the lower end of the lower tapered end 86 is received into the thrust bearing 90 at the base of the main housing.

It will be seen from the above description that main block 83 which has shaft 92 for the sheave 34 pivots about its own generally vertical axis in an arc in excess of 200 degrees. Obviously it would be quite possible for the haul back block and sheave to rotate a full 360 degrees. It will be readily appreciated that the main housing 40 can be cast as a single unit with the bearing cage 78 and the main block support tube 82 also each formed separately. Thus, when the elements are ready to be assembled, the main block can be first inserted at its lower end and then the bearing cage 78 dropped in on the upper end and bolted in place. It will be appreciated that the stem 62 of the haul back block 64 has support flanges 94 for determining the depth to which it is allowed to be received into the main support section 48. Since the stem 62 is freely pivotable a holding means 96 is attached to the upper part 50 of the main housing 40 to restrain the haul back block from any axial movement or from being accidentally flipped out of its bearing structure.

Because conventional tower tops have pivoted both the main and haul back sheaves or blocks on the same axis it has been necessary to run the main and haul back cables close together thus causing rubbing and twisting and consequent rapid wear. The unique tower top of this invention permits the haul back block to be supported quite near its sheave axis. In other words, the main housing 40 of this tower top acts as a rigid extension of the tower and brings rigid support up to the sheave axis 70. In like manner the main sheave has rigid structure both above and below in which to be mounted. In this manner bearings are permitted to be smaller than they would be in an instance where all of the thrust had to be taken below the shaft 92 of the sheave. Since the moments created by the stresses on the haul back and main sheaves have been reduced by raising rigid supporting structure higher with relation to the axes of rotation of the sheaves, the bearing structure for the haul back block can also be 70 lighter. The total result is a light and stronger and more dependable tower top.

It will be noted from the drawings that the tower top 30 is provided with a series of eyes or holes through which the U-shaped guy line shackles 21 are looped. Each 75

shackle has attached thereto the block side plates 23 which carry a sheave 25 therebetween. The shackles are secured to the block side plates by shackle bolts 29. Such guyline structures are conventional in the art and are only described in order to complete a picture of the environment in which the invention is used.

It will also be noted, particularly by reference to FIG. 3 that the tower top may be modified somewhat and still retain its advantages. Thus, the main block and its housing may be pivotally secured by a stem journaled in the upper end of the spar. In this way the main sheave 34 will have its tubular block housing closed as along line 85, thus dispensing with the upper bearing structure for said main block housing. However, additional rigid structure 73 will have to be provided on the base portion of the lower top housing, together with added bearings 75 and stem 77 at the lower end of the tubular main block housing. In this way, the spirit and principle of the preferred form of the invention is retained.

The foregoing is considered as illustrative only of the principle of this invention. Since numerous modifications and changes will readily occur to those skilled in the art, it is not desired to limit the invention to the exact construction shown and described.

What is claimed is:

1. A tower top and fairleader assembly for a generally vertically disposed portable logging spar, comprising:
  - (a) a main tower top housing mounted on the top of said spar including a first tubular section being open at both its upper and lower ends;
  - (b) a base section extending generally outwardly at a right angle to said first tubular section and having a cable opening therein;
  - (c) a top support section extending generally outwardly at a right angle to said first tubular section and having a bearing cage means detachably mounted therein generally coaxially with said cable opening in said base portion;
  - (d) a first block means with tubular stem means pivotally mounted and received within the upper portion of said first tubular section;
  - (e) a second generally tubular block support section pivotally supported by said bearing cage and by bearing means concentrically disposed around said cable opening for pivoting in non-concentric but generally parallel relation to said first block means; and
  - (f) said housing with said first and second tubular block sections being mounted at an angle on said vertically disposed spar so that said block sections pivot at an angle to said spar, the lower open end of said first tubular section located generally outside the vertical plane of the walls of said spar, said angular mounting of said tubular sections permitting cables to pass downwardly from said housing and the topmost portion of said spar outside said spar.
2. A tower top and fairleader assembly for a generally vertically disposed portable logging spar, comprising:
  - (a) a main tower top housing mounted on the top of said spar including a first tubular section being open at both its upper and lower ends;
  - (b) a base section extending generally outwardly at a right angle to said first tubular section and having a cable opening therein;
  - (c) a top support section extending generally outwardly at a right angle to said first tubular section and having a bearing cage means detachably mounted therein generally coaxially with said cable opening in said base portion;
  - (d) a first block means with tubular stem means pivotally mounted and received within the upper portion of said first tubular section;
  - (e) a second generally tubular block support section pivotally supported by said bearing cage and by bearing means concentrically disposed around said cable opening for pivoting in non-concentric but general-

ly parallel relation to said first block means, said bearing cage being generally on a level with said stem means of said first block means; and
 (f) said housing with said tubular sections being mounted at an angle on said vertically disposed spar with the lower open end of said first tubular section located generally outside the vertical plane of the walls of said spar, and said housing having all bearing structure located generally above its mounting on said spar.
